UNITED STATES PATENT OFFICE.

ZACHARY TAYLOR JONES, OF NEW YORK, N. Y.

DESIGN FOR A CHANNEL-IRON.

SPECIFICATION forming part of Design No. 25,411, dated April 21, 1896.

Application filed March 18, 1896. Serial No. 583,820. Term of patent 14 years.

To all whom it may concern:

Be it known that I, ZACHARY TAYLOR JONES, a citizen of the United States, residing in the city of New York, county and State of New York, have invented and produced a new and original Design for a Channel-Iron, of which the following is a specification, reference being had to the accompanying drawing, which forms a part hereof.

10 The drawing represents in perspective a short length of channel-iron which embodies my design.

In accordance with my design the two lateral members or webs $\alpha\alpha$ of the channel stand each at an angle less than a right angle with the middle member b , inclining toward each other, as represented.

The leading feature of the design is the inclination of the lateral members or webs with respect to the middle member and to each other.

What I claim as my invention, and desire to secure by Letters Patent, is—

The design for a channel-iron, substantially as shown and described.

25 This specification signed and witnessed this 11th day of February, A. D. 1896.

ZACHARY TAYLOR JONES.

In presence of—

HENRY RAINY,
HERMAN STEIGER.
